UNITED STATES PATENT OFFICE.

ROBERT K. COLLINS, OF CANTON, NORTH CAROLINA.

COMBINATION SQUARE.

Application filed March 10, 1924. Serial No. 698,119.

The object of the invention is to provide a tool particularly adapted for laying off and finding the right lengths of the various kind of rafters encountered in roofs of 5 pitched construction, so that the various lengths may be readily determined from the indicated difference between the rafters.

With this object in view the invention consists in a construction and combination of 10 parts of which a preferred embodiment is shown in the accompanying drawings, wherein:

Figure 1 is a plan view of the invention.

Figure 2 is a sectional view on the line

15 2—2 of Figure 1.

The invention comprises the main and supplemental squares 1 and 2 and a plurality of blades 3 preferably of varying lengths as indicated at 3^a, 3^b and 3^c. The square 1 on 20 one edge of one of its arms is provided with graduations 4 preferably in sixteenths and on the other edge with graduations preferably in twelfths of an inch, the supplemental square being similarly divided as 25 indicated at 6 and 7 respectively. Similar divisions are also made on the blades 3^a, 3^b and 3^c as indicated generally at 8 and 9.

Both arms of the main square 1 are slotted longitudinally as indicated at 10 and the 30 supplemental square also slotted as indicated at 11, likewise the blades are formed with longitudinal slots 12. Preferably the slots 10, 11 and 12 are formed with inclined side walls as indicated at 13 in Figure 2 to 35 make them cross-sectionally trapezoidal for the reception of flat head screw bolts 14 the shanks of which pass through the slots of connected members as indicated in Figure 1 and receive the hand screws 15 by which 40 angular positions at which it is desired to dispose the different elements may be maintained.

The length of the common rafters is found by laying off on one leg of the square 1 the 45 span of the roof and then laying off on the other leg the height of the hip above the wall plates. The one leg of the supplemental square is then disposed diagonally

across these points and the length indicated on its edge is the length of the common 50 rafter. The lengths of the hip rafters are then determined by the blade 3^c by laying off on the other leg of the supplemental square a distance equal to the span of the hip rafter in a horizontal plane. Securing 55 the blade 3^c at this point on the leg of the supplemental square and connecting it with the point of connection between the supplemental square and the main square will indicate on the blade 3^c the length of the hip 60 rafter, or the valley rafter if it is the length of the latter that is sought. The jack rafters are then found by disposing the blades 3^a and 3^b at specified distances on the short leg of the supplemental square between 65 the point of connection of the leg with the main square and the point of connection with the blade 3^c, the blades 3^a and 3^b being disposed parallel with that leg of the supplemental square which spans the legs of the 70 main square. Where these blades 3^a and 3^b cross the blade 3^c, the lengths of the different jack rafters will be indicated.

Having described the invention, what is 75 claimed as new and useful is:

A combination tool comprising main and supplemental squares and a plurality of blades, means for connecting the squares with the longer leg of the supplemental square in spanning relation with the angle 80 of the main square, and means for clamping one of the blades in spanning relation with the angle of the supplemental square and the remaining blades in parallelism with the longer leg of the supplemental square and 85 in corresponding relation with the first said blade, the legs of both squares being slotted longitudinally and the blades being provided with longitudinal slots, the clamping means consisting of bolts passing through said slots 90 to provide for relative adjustment of the several elements.

In testimony whereof he affixes his signature.

ROBERT K. COLLINS.
